UNITED STATES PATENT OFFICE.

DAVID STUTZMAN, OF LIGONIER, INDIANA.

FRUIT-DRIER.

SPECIFICATION forming part of Letters Patent No. 284,922, dated September 11, 1883.

Application filed July 2, 1883. (No model.)

To all whom it may concern:

Be it known that I, DAVID STUTZMAN, of Ligonier, in the county of Noble and State of Indiana, have invented certain new and useful Improvements in Fruit-Driers; and I do hereby declare the following to be a full, clear, and exact description of the invention, such as will enable others skilled in the art to which it pertains to make and use it, reference being had to the accompanying drawings, which form part of this specification.

My invention relates to an improvement in fruit-driers; and it consists in the combination of the drier with pivoted legs, which are attached thereto, so as to raise the drier when in use above the top of the stove, and pivoted side doors, which can be let down, so as to catch the heat from the stove directly through the drier, as will be more fully described hereinafter.

The object of my invention is to provide a drier which can be placed upon the top of a cook-stove, and which will allow the cooking to be done while the drier is in position, and thus not only not interfere with the operation of the drier, but have the drying proceed while the cooking is being done.

Figures 1 and 2 are vertical cross-sections of my invention, taken at right angles to each other, the folding parts being shown in one position in solid lines and in another position in dotted lines.

A represents the drier, which has double walls on its ends and suitable spaces between them for the free upward passage of the heat. Through the inner walls are cut a suitable number of slots, B, and the cut-away metal C is turned outward over the flues through which the heat rises, so as to catch the heat and deflect it into the frame under the trays upon which the fruit, berries, or other article being dried is placed. The frames of the trays D are made solid, so as to extend across the frame from side to side, and have the central openings, E, through them, which openings are not covered by the wire-gauze, and which are intended to be always open, so as to allow a free passage of the heat and moisture through the frame. By making the frames in one solid piece, as shown, all supports for the frames, with the exception of those upon which the

ends rest, are entirely done away with. The heat rises from the stove against the curved bottom F of the drier, and then passes up upon each side through suitable openings made 55 in the side of the frame into the flues. All of the heat which is not caught by the turned-out parts C and deflected directly in through the drier passes up through the passages H at the top into the top of the frame, and thence 60 out through the opening I.

Pivoted to each of the corners of the frame, inside of its outer walls, is a leg, J, which has a T-shaped slot made through its upper end for the pivotal bolt or screw to pass through. 65 The slots are made T-shaped, so that the legs can be turned outward when the drier is in use, or can be folded up when the drier is being transported or not in use. When the legs are lowered into position so as to support the 70 drier, the pivotal bolt or screw passes through that portion of the slot which is parallel with the length of the leg. When, however, the legs are folded up for transportation, that portion of the slot which extends at right angles 75 to the length of the leg is brought opposite to the pivotal bolt or screw, the leg is then moved inward the full length of this portion of the slot, and the leg is then turned at right angles, as shown in dotted lines. This closes the leg 80 up within the frame, so that it will not project and take up unnecessary room either during transportation or when the drier is packed away.

Above each one of the legs projects a suitable lug, L, which catches in a notch made in the top of the leg, and thus prevents the legs from accidentally closing in while the drier is in use. While the legs are in a vertical position they are braced not only by having their 90 outer edges bear against the sides of the frame, but by the stops or projections which catch in the notches formed in their upper ends.

After the legs have been adjusted in a vertical position and the drier placed upon the top of the stove the side doors, N, which are hinged at their upper edges to the sides of the frame, are turned downward, as shown in solid lines, so as to catch all of the heat which rises from the stove just under the drier. These 100 doors serve as conductors for the heat, and compel it to rise directly up through the drier.

When cooking is to be done upon the stove, it is not necessary to remove the drier, for the doors, which are in the way, can be turned up against the side of the frame, and the cooking utensils be placed upon the stove as though the drier was not in use. By means of this construction the regular family cooking can be done at the same time that articles are being dried, for the heat from the stove then rises up through the drier, as usual, but not in so great a quantity. As soon as the cooking is done, those doors which have been opened upward can be closed down again.

The trays are inclined from the ends upward toward the center, so as to cause the heat to pass evenly over the bottom of the tray toward the center. Were the trays flat, the heat would have a tendency to pass through any part of the tray, and thus portions of the article being dried would receive more benefit from the heat than others.

Having thus described my invention, I claim—

1. A drier provided with folding legs and

doors which can be closed down around the 25 legs, substantially as shown.

2. In a drier which is adapted to be placed upon the stove, the combination of the legs, provided with T-shaped slots, and having notches in their upper ends, suitable stops to 30 catch in the notches, and the folding doors, substantially as described.

3. A drier having double walls at opposite ends, and having the slots B and turned-out portions C for catching the heat and deflecting it from the flues into the frame, in combination with suitable folding legs and the hinged doors, which are attached to the sides of the frame, substantially as specified. 35

4. In a drier, a tray which is raised at its 40 center and provided with an opening through which the heat passes, substantially as shown.

In testimony whereof I affix my signature in presence of two witnesses.

DAVID STUTZMAN.
